UNITED STATES PATENT OFFICE.

EDWARD B. ALLEN, OF PORTLAND, MAINE, ASSIGNOR OF ONE-HALF TO
WALTER B. SAWYER, OF SAME PLACE.

CHANNEL-CUTTING DEVICE FOR SOLE-SEWING MACHINES.

SPECIFICATION forming part of Letters Patent No. 398,305, dated February 19, 1889.

Application filed November 24, 1888. Serial No. 291,794. (No model.)

To all whom it may concern:

Be it known that I, EDWARD B. ALLEN, of Portland, county of Cumberland, State of Maine, have invented an Improvement in Sole-Sewing Machines, of which the following description, in connection with the accompanying drawings, is a specification, like letters on the drawings representing like parts.

This invention has for its object to improve that class of sewing-machines in which the work is supported upon a horn while being stitched. In this class of machines it is a desideratum to embed the stitch in a channel at the inner face of the inner sole next the foot of the wearer. I have provided the horn with a channel-cutter to cut a channel in the inner sole as the shoe is being stitched on the horn. It will be understood that the horn is rotated by hand as the sole is being stitched or secured to the lasted upper, and that the boot or shoe is fed over the horn in different directions as the stitching is carried about the sole. The channel-cutter must always occupy a position just behind the hole through which the fastener (herein supposed to be a stitch) passes to enter the leather to secure the sole and upper together; and to keep the channel-cutter in the proper position, notwithstanding the rotation of the horn, so that it will cut a groove in the material just in advance of the stitch to be made therein, I have combined with the said channel-cutter means to rotate it as the horn is rotated, whereby the channel-cutter always presents its cutting-edge toward the direction from which the material is being fed over the horn.

My invention consists in the combination, with a rotating horn, of a channel-cutter; also, in the combination, with a rotating horn and a channel-cutter, of means for rotating the said channel-cutter in the horn as the latter is rotated.

Figure 1 in section and elevation shows a sufficient portion of the horn of a sole-sewing machine to enable my invention to be understood; Fig. 2, an enlarged sectional detail of the upper end of the horn, showing the usual whirl and my improved channel-cutter. Figs. 3 and 4 show a side view and a top view of the channel-cutter. Fig. 5 shows a piece of

a boot or shoe with stitches drawn into the channeled inner sole.

The frame or stand A, the horn-shaft A', the horn A², the whirl a at the apex of the horn, and the shafts a' a², and the gearing a³ a⁴ a⁵ 55 a⁶, to retain the whirl in proper position with relation to the hook of the usual needle, (not shown,) and to actuate the whirl always at the proper time and for the proper distance in the proper direction to lay the usual thread carried by the whirl into the hook of the usual hooked needle, are all as common in the well-known McKay sole-sewing machine, except that herein the shaft a' is hollow or tubular, so the said parts need not be herein further 65 described, in so far as they operate in well-known manner.

I have provided the top of the horn above the usual whirl with a channel-cutter, shown as a ring, b, provided with a blade, b', sharpened at one edge, as best shown in Fig. 4, the said ring at its under side having gear-teeth, as b².

The teeth b² of the channel-cutter are engaged by the beveled teeth (see Fig. 2) at the 75 upper end of a cutter-operating shaft, c, extended through the hollow whirl-actuating shaft a'.

The lower end of the shaft c has a bearing at c', and has connected to it a bevel-gear, c², 80 which is engaged by a bevel-gear, c³, on a shaft, c⁴, having its bearings at c' and c⁵, the said shaft having a bevel-gear, c⁶, the teeth of which are engaged with the teeth of a stationary bevel-gear or toothed ring, c⁷, held in fixed 85 position with relation to the horn, so that when the horn is rotated in usual manner during the stitching of the material therein the channel-cutter will be rotated correspondingly to always present the sharp edge of the blade b' 90 in the direction from which the material is approaching to be united.

I do not desire to limit my invention to the exact form of cutter shown, nor to the exact form of devices represented by which to rotate the channel-cutter.

Fig. 5 shows the outer sole, e, which may be of any usual kind; e', the inner sole; 2, the channel cut in the latter, and e² the fasteners, shown as stitches.

I claim—

1. The combination, with a rotating horn, of a channel-cutter mounted in the tip of the horn, substantially as described.
- 5 2. The combination, with a rotating horn and a channel-cutter mounted in the tip of the horn, of gearing to rotate the said channel-cutter, substantially as described.

In testimony whereof I have signed my name to this specification in the presence of two subscribing witnesses.

EDWARD B. ALLEN.
